UNITED STATES PATENT OFFICE

MORRIS SALZMAN, OF BROOKLYN, NEW YORK, ASSIGNOR TO UNIVERSAL PERMANENT WAVE MACHINE CORPORATION, OF NEW YORK, N. Y., A CORPORATION OF NEW YORK

CURLING ROD

Application filed September 6, 1928. Serial No. 304,374.

The invention relates to hair curlers or curling sticks of the type used in the art of permanent hair waving in which a strand of hair is secured at one end to the rod and wrapped tightly about the rod before the wrapped strand is inserted in the usual electric heater.

More specifically defined, the invention relates to that type of hair curler comprising an outer tube and an inner rod in which the hair is wrapped about the outer tube and is turned into tightened position by the rotation of a handle at one end of the curler which acts through the centrally positioned rod to turn the end to which the hair is attached. It is required in such constructions that there be a freedom of relative movement between the outer tube and the inner rod when turning in one direction and a restraint to any such freedom of relative movement to any attempt to turn in the opposite direction. Numerous schemes have been suggested usually involving the use of some form of one way ratchet connection for effecting this purpose but usually such constructions are difficult to make, require the use of expensive machining, all of which adds materially to the cost of manufacturing such devices.

Accordingly, the primary object of the invention is to provide a simplified form of one way clutch mechanism which will provide for the requisite resistance to rotary movement in one direction and freedom of rotary movement in the opposite direction and at the same time provide a simplified form of construction which can be manufactured cheaply.

Primarily, this object is attained by positioning between the outer tube and the inner rod a spiral spring with one end secured in place and the parts so proportioned and arranged that the turns of the spring will fit snugly in the outer tube and thus provide a smooth bearing between the clutch spring and outer tube.

Still another object of the invention is to provide a configuration of hair curler which will be free of projections and thus permit of an easy withdrawal of the curler from the finished strand without danger of be-

coming entangled in the permanently waved hair strand.

Various other objects and advantages of the invention will be in part obvious from an inspection of the accompanying drawings 55 and in part will be more fully set forth in the following particular description of one form of mechanism embodying the invention, and the invention also consists in certain new and novel features of construction 60 and combination of parts hereinafter set forth and claimed.

In the accompanying drawings,

Fig. 1 is a view in side elevation of a hair curler constituting a preferred embodiment 65 of the invention and showing a strand of hair tied thereto at one end and loosely wound about the outer tube;

Fig. 2 is a view largely in axial section and with parts broken away showing in detail 70 the novel features of the hair curler shown in Fig. 1; and

Fig. 3 is a transverse sectional view taken on the line 3—3 of Fig. 2 looking in the direction indicated by the arrow. 75

In the drawings and referring first to Fig. 1, there is disclosed part of a person's head A extending from which is a hair strand B, secured adjacent the head A to one end of the curler by means of a string C. 80

The curler 10 comprises an outer hollow tube 11 slightly tapered from a strict cylindrical form. In the smaller end 12 of the tube 11 is rotatably mounted an end or tying piece 13 provided with means hereinafter 85 more fully described for securing the curler to the hair strand B. Rotatably mounted in the other end of the tube is a head 14 the externally projecting portion 15 of which constitutes a finger piece knurled to provide 90 a roughened surface. The head 14 includes a cylindrical bearing portion 16 rotatably mounted within the outer tube. Within the bearing portion 16 the head 14 is reduced to provide a sleeve or extension 17 spaced from 95 the inner wall of the tube 11. An inner rod 18 extends axially of the tube 11 with one end threaded into the end piece 13 and the other end in threaded engagement with the extension sleeve 17. 100

Positioned in the space between the outer tube 11 and the sleeve 17 is a spiral spring 19, one end 20 of which is bent inwardly and extends through a radially disposed slot 21 formed in the sleeve 17 as shown in Fig. 3. It is understood that the upper or outer end 22 of the spring is free and that the spring is proportioned so that it will have a snug, light frictional engagement with the inner side of the outer tube.

Referring to the end piece it is provided with an annular tying groove 23 and is also provided with a slot 24 extending from the outer free end 25 axially and diametrically along the projecting portion of the end piece to the groove 23.

The device also features a substantially smooth slightly tapered outer surface extending from the groove 23 to the end 26 of the finger piece 15. This construction permits the ready withdrawal of the device as a whole from the hair strand without possibility of projections entangling in the hair as is common with some forms of similar devices now in general use.

In operation it will be understood that the hair strand B is engaged adjacent the head A by means of a string or similar flexible fastening means C which is tied to the strand. The ends of the string are then wrapped one or more times about the groove 23 and the loose ends drawn through the slot 24. This construction is found to be effective in holding the curler in position relative to the hair strand and secured against endwise movement. The hair is then wrapped conventionally about the hair receiving surface provided by the outer tube and then by engaging the finger piece and turning the same in the direction indicated by the arrow in Fig. 2, the hair strand is wrapped tightly about the curler. When sufficiently wrapped, the free end of the hair strand is secured conventionally.

It is understood that during this winding movement the turning of the finger piece has a tendency to reduce the normal diameter of the clutch spring thus permitting the spring and with it the inner rod and its associated end pieces to turn freely in the outer tube. Subsequently any tendency of the hair strand to cause a reversal or unwinding movement will be resisted by the clutching engagement of the sides of the spring when distended in their contact with the inner face of the outer tube.

In case there is damage to the clutch spring it is simply necessary to unscrew the end pieces, remove the damaged spring and re-place a new spring after which the parts are remounted and the curler is again in condition for use.

I claim:

1. A curling rod for use in curling hair in the art of permanent hair waving, comprising

an outer tube having an end piece rotatably mounted at one end and a turning head rotatably mounted at the other end, and means within the tube connecting the end piece and head to form a unit mounted for rotary movement relative to the tube, one way clutching means for permitting a rotation of the unit in one direction and restraining such rotation in the opposite direction, said means including a spirally wound spring with its turns having a frictional fit in the tube and having one end secured to the unit.

2. A hair curler including an outer tube, an end piece rotatably mounted in one end of the tube and projecting therefrom, the projecting portion of said end piece provided with a tying slot, a cylindrical finger piece rotatably mounted in the other end of the tube, projecting therefrom, and forming in effect a continuation thereof, the external surface defined by the outer tube, the finger piece and the portion of said end piece between the slot and the outer tube being slightly tapered and forming a frusto-conical surface free of projections.

3. A hair curler comprising an outer hollow tube, an inner rod formed of a plurality of parts demountably secured together end to end, and one of said parts constituting a tying piece rotatably mounted in one end of the tube, another part constituting a finger piece rotatably mounted in the other end of the tube and provided within the tube with an extension spaced from the inner wall of the tube, said rod having a freedom of rotary movement in one direction relative to the tube and means for securing the rod and tube frictionally from rotating freely in the opposite direction, said means including a single spiral spring having one end secured to the finger piece extension, fitted between the extension and tube and having one of its turns bearing against the tube.

Signed at New York, in the county of New York and State of New York, this 20th day of July A. D. 1928.

MORRIS SALZMAN.
